F. RIES

EXPLOSIVE PACKAGE AND CARRIER

Filed Jan. 17, 1927

UNITED STATES PATENT OFFICE.

FREDERICK RIES, OF COMPTON, CALIFORNIA.

EXPLOSIVE PACKAGE AND CARRIER.

Application filed January 17, 1927. Serial No. 161,547.

- My invention relates to the packing and transportation of explosives and particularly those explosives that are set off or exploded as a result of jar or percussion, and the principal object of my invention is to provide a relatively simple, practical and efficient package and carrier for explosives that will enable the containers of the explosives to be packed and transported to the points of use with a maximum degree of safety and the packages of explosives being adapted to be positioned in protective carriers that are arranged on air craft and particularly air craft that is utilized in war.
- 15 Further objects of my invention are to provide an explosive package and carrier that offers a maximum degree of safety to the explosive container against gun-fire, shocks and vibration and fire.
- 20 With the foregoing and other objects in view, my invention consists in certain features of novelty and arrangement of parts that will hereinafter be more fully described and claimed and illustrated in the accompanying drawing, in which—

Fig. 1 is a top plan view of an aeroplane that is equipped for handling my improved explosive packages.

Fig. 2 is an enlarged cross section taken approximately on the line 2—2 of Fig. 1.

Fig. 3 is an enlarged vertical section taken approximately on the line 3—3 of Fig. 2.

Fig. 4 is a detail section showing the bayonet joint connection between the explosive package and the carrier therefor.

Referring by numerals to the accompanying drawing, 10 designates the fuselage of an aeroplane and formed in the sides thereof, preferably toward the rear, are pockets or chambers 11 that receive the housings or carriers for the explosive packages. Each housing consists of an outer shell 12 of suitable sheet metal, the top or upper end 13 of which is rounded and the lower end of this housing is closed by a hinged plate or door 14. The inner edge of this plate or door is connected by a hinge 15 to the lower end of the inner wall of the housing 12 and the outer edge of said door is secured by a suitable latch 16 to the lower edge of the outer wall of the housing. Suitable means may be provided to release the latch 16 and, when released, the door 14 will, by gravity, swing downward into a vertical plane as illustrated by dotted lines in Fig. 3.

Housing 12 is positioned in the chamber of

pocket 11 and is supported therein by means of suitable shock absorbers 17 which may be of any desired form, either pneumatic, hydraulic, or of the type including rubber or 60 springs.

Arranged on the inner surface of the wall 12 of the housing, is a layer 18 of asbestos or analogous fire-proof material and arranged against this layer of asbestos, is a wall 19 65 of sponge rubber, i. e. rubber that is filled with small air chambers. Arranged against this wall of sponge rubber, is a layer 20 of saw-dust and immediately against said layer of saw-dust, is a layer 21 of cotton. Positioned against this layer of cotton, is a layer 22 of wool with which is incorporated pulverized cork or comminuted sponge. The layers of wool, cotton and saw-dust are separated and held in place by any suitable soft 70 fabric such as cheese-cloth or silk gauze.

Arranged against the inner face of the layer 22 of wool, is a thin wall 23 of aluminum and the lower ends of the sides of this aluminum wall terminate a short distance 80 above the plane occupied by the lower ends of the side walls of the outer housing 12.

Arranged between the lower portions of the side walls of housing 12 and the inner member 23, are plates 24 upon which the lower 85 ends of the layers of material 18 to 22 inclusive rest. Arranged on the under surface of the rounded upper portion of inner wall 23, is a cushioning member 25 of soft elastic material such as sponge rubber and which serves 90 as a seat or bearing for the rounded upper ends of the explosive containing packages.

It will be understood that the housing for the explosive packages is of sufficient length to accommodate a number of the packages and 95 each of the latter includes an outer shell 26 of suitable sheet metal, which shell is substantially cylindrical in form and provided with a rounded upper end 27 that is adapted to fit snugly against the cushioning 100 member 25 within the housing.

Projecting outwardly from the lower portion of each cylindrical housing 26 and on opposite sides thereof, are pins 28 that are adapted to enter bayonet slots 29, the 105 latter being formed in the lower portions of the inner walls 23 of the housing and by such arrangement, the packages for the containers of the explosive may be removably secured within the housing of the carrier.

Arranged against the inner face of the wall 26 of the package, is a layer 30 of as-

bestos and arranged directly on this layer of asbestos, is a layer 31 of sponge rubber. Arranged against said layer of sponge rubber, is a layer 32 of saw-dust and upon the latter is arranged a layer 33 of cotton. Arranged against said layer of cotton, is an inner layer 34 of wool having incorporated therewith pulverized cork or comminuted sponge. The layers of material 31 to 34 inclusive are separated by suitable soft fabric such as cheese-cloth or silk gauze.

Connected by a hinge 35 to the lower edge of the metal shell 26 of the package, is a plate 36 that functions as a closure for the lower end of said package and said door is adapted to be retained in closed position by means of a suitable latch 37. Arranged on the inner face of the door 36 is a layer 37^a of asbestos and arranged on the latter, are cushioning layers of sponge rubber, saw-dust, cotton and wool, the arrangement being the same as on the inner surface of the shell 26.

The chamber 38 within the package just described is adapted to be occupied by the bottle 39 that contains the explosive such as nitro-glycerine and it is the intention that the explosive containers be placed in the packages at the point where said containers are filled and thus the containers in the cushioned packages may be safely transported to the aeroplane where they are installed in the cushioned housings and secured therein by the engagement of the pins 28 in the bayonet slots 29.

After the packages have been placed in the cushioned housings, the doors 14 of said housings are closed and latched and thus the containers of the high explosive are carried in cushioned packages, which in turn are positioned in the cushioned housings, thus minimizing the danger of explosion due to vibration or percussive blows.

The outer shell 12 of the housing provides an effective armor against projectiles and in the event that the housing receives externally delivered blows, the force of the latter will be absorbed by the cushioning elements that line the housing and the packages.

When the containers of explosive are carried by an aeroplane engaged in warfare and it is desired to drop the containers from the plane while the same is in flight, the latch 16 that normally holds door 14 in closed position is released and said door will swing downward into a vertical plane by gravity and the latch 37 that holds the door of the package in closed position is then released and said door will likewise swing downward into a vertical position, thus permitting the container 39 to drop and explode when it strikes the ground, a building or a ship.

While I have shown my improved explosive package and carrier as being applied to an aeroplane, it will be understood

that the same construction may be utilized on all forms of air craft and, where the explosive containing packages are to be transported for a considerable distance, the housings may be applied to railway cars, boats, 70 motor trucks, or the like, thus enabling the explosive containers to be conveyed for considerable distances with minimum danger of explosion from shocks or vibration.

It will be understood that minor changes 75 in the size, form and construction of the various parts of my improved explosive package and carrier may be made and substituted for those herein shown and described without departing from the spirit of 80 my invention, the scope of which is set forth in the appended claims.

I claim as my invention:

1. In an explosive package and carrier, the combination with a housing comprising 85 inner and outer walls of metal, a plurality of layers of cushioning material arranged between said walls and a door for normally closing the bottom of said housing, of an explosive container package removably positioned within said housing and comprising an outer wall of metal, a plurality of layers of cushioning material arranged within said wall, a metal door normally closing the lower end of the explosive container package, and 90 a plurality of layers of cushioning material arranged upon the inner surface of said door.

2. In an explosive package carrier, a housing of sheet metal open at its lower end, a gravity door hinged to the lower portion 100 of said housing and adapted to normally close the opening at said lower end, a layer of fire-proof material on the inner surface of the wall of said housing, a plurality of superimposed layers of cushioning material arranged within said housing with the outer layer in contact with said layer of fire-proof material, a metal wall disposed against the inner layer of cushioning material, a layer 105 of cushioning material arranged on the surface of said metal wall at the upper end thereof, a cushioned explosive container package removably positioned within said housing with its upper end normally bearing 110 against the cushioning material at the upper end of the inner metal wall thereof, a door normally closing the lower end of said explosive container package, and a plurality of layers of cushioning material arranged on the inner face of said door.

3. In an explosive package and carrier, the combination with an internally cushioned housing, of an explosive containing package removably positioned within said housing and comprising a metal shell, a lining of fire-proof material for said shell, a plurality of superimposed layers of cushioning material arranged within said shell with the outer layer disposed adjacent to the layer of fire-proof material and a cushioned door nor- 125 130

5 mally closing the lower end of said cushioned shell which door comprises an outer plate of metal, and a plurality of superimposed layers of cushioning material arranged upon the inner face of said metal plate.

4. The combination with a carrier, of a sheet metal housing, shock absorbers mounted on the carrier and supporting said sheet metal housing, a gravity door normally closing the lower end of said housing, a plurality of super-imposed layers of cushioning material arranged within said housing against the wall thereof and a cushioned explosive containing package removably positioned within 10 said cushioned housing.

15 within said cushioned housing.

5. The combination with a carrier, of a sheet metal housing, shock absorbers mounted on the carrier and supporting said sheet metal housing, a gravity door normally closing the lower end of said housing, a plurality 20 of super-imposed layers of cushioning material arranged within said housing against the wall thereof, a cushioned explosive containing package removably positioned within said cushioned housing and a cushioned 25 gravity door normally closing said cushioned package.

In testimony whereof I affix my signature,

FREDERICK RIES.
